UNITED STATES PATENT OFFICE.

DAVIS S. WILLIAMS, OF LOS ANGELES, CALIFORNIA.

GAME.

Application filed February 7, 1928. Serial No. 252,466.

This invention relates to an indoor or table football game in which provision has been made to duplicate and carry out the moves, formations and plays of the actual game.

5 The improved game comprises the use of men (miniature players) of a novel construction, a means for activating the men, and means for kicking or punting and passing the ball, thereby allowing the game to be played practically in accord with standard rules and regulations of the real game.

An object of this invention is to provide an indoor football game in which the element of chance or luck is blended with, and modified by, the skill of the players, as in the actual game.

Another object is to provide a novel and improved form of men with which an indoor football game may be played.

20 Another object is to provide an indoor football game embracing a combination of men of specific construction and activating means.

These, and other objects and results of my invention will become apparent from the following detailed description of the elements embraced by my invention and defined in the appended claims. Other forms of indoor games simulating the outdoor game of football or rugby, have been invented hitherto, 25 but none of these prior games have utilized men or game pieces of the particular construction and mode of operation which I have invented. Neither have these prior game pieces or men been activated, put into play 30 and caused to carry out the plays in the manner to be hereafter disclosed by me. Furthermore, some of the prior games were so designed that physically stronger players had a great advantage over the weaker players, 35 while the game herein disclosed nullifies or 40 modifies such elements of physical strength and introduces an element of skill which enhances the scope of, and pleasure derived from the game.

45 Reference will be made to the appended drawings, which show, merely for the purpose of illustrative disclosure, a preferable embodiment of my invention, it being expressly understood that various changes and 50 modifications may be made in practice within the scope of the claims, without departing from my invention.

In the drawings:

55 Figure 1 is a side elevation of one form of game piece or man and activating means, the man being in position for a forward pass.

Figure 2 is a side elevation of another form of game piece or man, activating means and kicking wedge, the man being in position for a punt.

60 Figure 3 is a plan view of the kicking wedge.

Figure 4 is a side elevation of the base portion of a man and a bottom view thereof.

65 Figures 5, 6, 7 and 8 are side elevations of modified base portions of men and bottom views thereof.

70 Figure 9 is a perspective view of a miniature football field showing the game pieces arranged thereon in a formation which may be adopted when a kick-off is being made and illustrating the use of the kicking wedge shown in Figure 3.

The game is played upon any table or other support of sufficient size to hold the field, 75 which may be made of any suitable fabric, paper, composition, such as linoleum or the like bearing the lines of a football field thereon. The playing field may be of any desired size, but in proportion to the regulation field, and may be surrounded by a suitable strip of neutral territory which may be bordered with a fence or border of approximately the size of the men so as to retain them on the table or field. The playing field 80 may be made of soft material, if desired, such as the flannel side of certain forms of oilcloth. Instead of with a stiff or hard fence or border, the playing field may be surrounded by a broad cloth, or other fabric tape, held in place 85 on the edge of the playing field by means of wire clips of suitable construction or other approved means. The use of a fabric or tape-like border has certain advantages over a hard border in that when struck by the men 90 or activating members the fabric border will give or yield slightly and thereby prevent rebound. The size of the field should be in proportion to the men, or vice versa; for example a field approximately sixteen inches 95 by forty-eight inches readily accommodates game pieces or men about one and a half inches in height. A suitable space may be left between the goal lines and border or fence at the end of the field for purposes which will 100 be apparent later.

105 In order to determine the yardage gained or lost, suitable markers or flags may be provided preferably of such form as to be adjustably positioned upon the fence or border surrounding the playing field. Two flags or markers connected by means of a cord or

other member representing a five or ten yard playing field space may be used, such markers being illustrated in the strip of neutral territory surrounding the field in Figure 9.

5 Goal posts of suitable size and construction are provided at the required points on or beyond the goal line. Such goal posts, made of paper, wire or light wood may be hingedly attached to the field and erected when 10 needed, or they may be detachably attached in any suitable manner.

Each player or side is provided with two types of game pieces or men. (Hereafter reference to men will relate to game pieces, 15 while the human player will be merely designated as player.) Each player has nine or ten men of substantially the type shown in Figure 1 and one or two men of substantially 20 the type shown in Figure 2. The total number of men on each side is eleven, as in actual football teams. Men of the type shown in Figure 2 are runners or ball-carriers, while the other men block, tackle, and otherwise enter into the play.

25 If desired, a certain number of men may be provided similar in a general way to the type shown in Fig. 1 with the exception that instead of having conical bottom surfaces, or axially placed projections upon the 30 surface of their base portions, these men may have flat bases. These men with flat bases may be used for linemen, the base construction offering greater resistance to impact and affording greater stability.

35 Both types of men are preferably substantially circular in horizontal section, are provided with a base 10, a body portion 11 and a head-like protuberance 12 and are suitably colored so as to bear a resemblance, grotesque, comical or realistic, to the actual football players. Preferably men on each side are distinguishably colored so as to identify the teams. The bottom surface of the 40 base 10 of men used as kickers, passers, or ball carriers, is preferably equipped with a diametrically disposed ridge (Fig. 7) or a centrally disposed protuberance, for example, the entire bottom surface of the base section 45 10 may be in the form of a low cone 13 so as to cause the men to assume a position at a small angle to the vertical. The purpose 50 of this construction will be later explained.

Runners or ball carriers of the type illustrated in Figure 2 are provided with a cavity 14 in the body portion 11 adapted to easily receive a miniature football 15. The football may be retained within the cavity by means of leather, rubber, wooden or fibrous arms 16 suitably attached or pivoted 55 at or near the shoulders of the men as indicated at 17. The football 15 may be made of any suitable material such as cork, light wood, composition, etc., and although having the general appearance and shape of a football, 60 it may be desirable to form the football with

a flat portion of its surface so as to prevent undue rolling thereof.

If desired, all men may be equipped with arms, as, for example, the arms shown in Fig. 2 on the ball carrier, so as to add to their 70 appearance and incidentally to prevent undue rolling when overthrown. These arms will furthermore help in blocking and give the effect of tackling. It is understood that the quality and workmanship of the men and 75 their similitude to real players may vary over a large range and I am not to be limited to the simple forms or design of men shown in the drawings, except as certain features of their construction enter into the game 80 as a whole. For example, certain of the men are to have a substantially centrally placed protuberance on the bottom surface of the base adapted to cause them to stand at an angle with the horizontal, but the men may 85 be made of wood, ivory or composition, and be circular, rectangular, polygonal or elliptical in cross section throughout their length or only in certain parts. Whatever construction 90 is used, a certain number of the men should be provided with conical, pyramidal or other irregular surface, such as that shown in Fig. 8, for example, adapted to cause men to assume a standing position at an angle with the horizontal. The protuberance upon 95 the base surface may be centrally disposed or it may extend diametrically along a transverse plane taken vertically through the men, so as to cause them to assume angles with the horizontal in a forward or backward position. Men of the type shown in Figures 100 1 and 2, or provided with bottoms of the type shown in Figures 4 and 7, are preferred.

In addition to a team of men each player is supplied with a number of activating disks 105 or pucks such as, for example, the disks 18. These disks or pucks may be made of light wood, composition, a phenolic condensate or any other suitable material, and should be of sufficient height to be able to hit the lower portion of the body of the men, as shown 110 in Figure 1.

A kicking wedge 19 is also provided, comprising a triangular body resting normally upon the hypotenuse or longer side. The other or upper two sides are provided with a groove 20 adapted to partially receive and 115 guide the ball when it is kicked from position in said groove. One of the grooves is preferably at a greater angle with the horizontal than the other so as to enable the players to execute high, short kicks or long punts.

The game may be played in fairly strict 120 accordance with the rules of the actual outdoor game or the players may formulate rules of their own. A few plays will be here described so as to illustrate the method of playing. Each player having been provided with 125 say, ten men as in Fig. 1 and the ball carrier as in Fig. 2, and also provided with three or 130

five activating disks, the players then position their men on the playing board or field as for a kickoff. Or each player may be provided with, say, seven flat base lines men, two 5 men of type illustrated in Fig. 1, and two ball carriers of type illustrated in Fig. 2. The player to kick off places his ball carrier as indicated in Fig. 2 before the kicking wedge 19 with the ball resting on groove 20 and in 10 contact with base 10 of the man. This is also shown in Figure 9. The men on the team to receive kickoff may be suitably disposed over their side of the playing board or field. If desired, the receiver's men may be placed on 15 their sides so as to offer more resistance. The player ready to kick off then snaps or shoots a disk with his fingers from behind the goal line at the ball carrier back of the kicking wedge and the disk comes in contact with the 20 base 10, knocking the base or "feet" of the man forward whereby the ball in the skid is kicked off. As soon as the ball is kicked fairly the receiving player may snap or shoot his disks to block the ball or the kicker's men, both 25 players shooting all of their disks in an effort to get their men closest to the ball, as after all of the disks have been snapped, the player whose man is touching or closest to the ball, gets the ball or the point where the 30 succeeding play starts is thus determined. If, after the initial kickoff, the ball is touching one of the receiver's men, he may elect to run back and this may be accomplished by halting the snapping of disks, placing the ball into the 35 receiver's ball carrier (but not moving the other men from their locations) and the player then driving his ball carrier into opponent's territory with his disks, the other player snapping his disks at the ball carrier 40 to stop him or at his own men to block the opponent. When all of the disks have been snapped they are retrieved, a new lineup formed and the game proceeds in the customary manner, a team having to make ten 45 yards in four downs to retain the ball.

In line plays, the player whose team has the ball, places the ball in the cavity within the ball carrier and sets up six or seven men on the line in desirable position and others 50 back of the line. The opposing player may then also arrange his men as desired to block the coming play. After both players announce their readiness, neither may touch the men except through the medium of disks 55 snapped at them. The disks may be directed against the ball carrier to make him rush the line, or against another man to bounce against the runner or the skid or kicking wedge may be used to cause the runner to hurdle the line. Kicks may be tried on third or fourth down to 60 gain yardage or a forward pass may be attempted. In order to pass, the ball is placed in front of a man's head as in Fig. 1 and a disk snapped at him. The men are so constructed that the disk 18 hits the man at the 65

lower portion of the body 11, thereby knocking the ball forward as the man pivots upon his conical or pyramidal base. To make a more forcible pass another man may be caused to lie down in front of the passer and hold 70 his "feet" in place.

It will be seen that practically all plays of the real game may be imitated with some degree of closeness and the game holds elements of exciting competition, increasing in 75 interest with the skill and ingenuity of the players. Any one with an elementary knowledge of the real game can play. Naturally, rules may be made by special agreement and a number are here suggested. It is a foul 80 to snap a disk directly at a ball. It is a foul to snap a disk so hard as to knock any man, disk or wedge beyond the border surrounding the field. (This restrains over-muscular players from monopolizing the game.) Disks 85 may be snapped from closer than the goal line under certain conditions and strong players may be required to snap their activating disks from a certain distance behind the goal line.

It will be seen that an important feature of 90 this invention resides in the game pieces or men used in playing the game. Certain of the men need have a base portion having a substantially centrally located protuberance on the bottom surface of such base. The body 95 portion of the men is also preferably separated from the base by representation of legs of reduced cross sectional area, and said body portion should be of sufficient size (at least of the same cross sectional area of the base) 100 so as to allow activating means to hit the body before hitting the base when the men are at an angle in the direction from which the disk is snapped.

I claim:

1. A game piece representing a football 105 player, having a base and a substantially centrally disposed protuberance upon the bottom surface of said base.

2. A game piece representing a football 110 player comprising a body portion, a base portion, a member of smaller cross section than said base portion connecting the same with the body portion, and a substantially centrally disposed protuberance upon the bottom 115 surface of said base.

3. A game piece representing a football 120 player comprising a cylindrical body portion, a cylindrical base, a member of smaller cross section than said base connecting the same with the body portion, and an inclined bottom surface on said base.

4. A game piece representing a football 125 player comprising a cylindrical body portion, a cavity in said body portion adapted to receive a representation of a football, arms attached to said body portion and adapted to cover said cavity, said body portion being connected to a base having an inclined bottom surface.

5. In an indoor football game, a plurality of game pieces representing football players, said game pieces being of substantially circular cross section and provided with a body portion, a base portion and a member of smaller cross section than said base or body portion connecting said base and body portion, and an inclined surface on the bottom of said base adapted to cause game pieces to assume positions at an angle to the vertical.
10
6. In an indoor football game, a plurality of game pieces representing football players, certain of said game pieces being of substantially circular cross section and provided with a body portion, a base portion and a member of smaller cross section than said base or bottom portion connecting said base and body portion, an inclined surface on the bottom of said base and a plurality of separate activating members of sufficient thickness to come in contact with the lower section of the body portion of said game pieces.
15
20
7. In an indoor football game, a representation of a football field, a plurality of game pieces representing football players, certain
25

of said game pieces being provided with a body portion and a base having a bottom surface adapted to cause game pieces to assume positions at an angle to the vertical and a plurality of separate activating members adapted to contact with either the body portion or the base of said game pieces when propelled thereagainst.

8. In an indoor football game, a representation of a football field, a plurality of game pieces representing football players, said players being provided with a body portion and a base having a bottom surface adapted to cause game pieces to assume positions at an angle to the vertical, a cavity in the body portion of some of said game pieces adapted to receive a representation of a football, arms pivotally attached to the body portions and adapted to cover said cavity, a plurality of separate, activating members adapted to contact with either the body portion or the base of said game pieces and a kicking wedge.

Signed at Los Angeles, California, this 31st day of January 1928.

DAVIS S. WILLIAMS.
